JAMES ALEXANDER FLANAGAN, OF TORONTO, ONTARIO, CANADA.

STITCH CONTROL FOR SEWING MACHINES.

1,404,357.

Specification of Letters Patent. Patented Jan. 24, 1922.

Application filed July 8, 1920. Serial No. 394,794.

To all whom it may concern:

Be it known that I, JAMES ALEXANDER FLANAGAN, residing at the city of Toronto, in the county of York and Province of Ontario, Dominion of Canada, have invented certain new and useful Improvements in Stitch Controls for Sewing Machines; and I hereby declare that the following is a full, clear, and exact description of the same.

10 This invention relates to a sewing machine provided with adjustable means, combined with the stitch control mechanism, for determining the length of stitch simultaneously for the forward and reverse feeds, and it 15 consists essentially of a lever for adjusting the stitch control mechanism, a pair of adjustable stops to limit the movement of the lever in opposite directions, and a right and left threaded screw for adjusting the stops

20 The invention further relates to means for moving the control lever between the stops to change the direction of the feed, this means comprising a rock shaft having a pair 25 of cranks, one of which is connected by a rod with the control lever, and the other of which constitutes the means by which the rock shaft is actuated, as hereinafter set forth and particularly pointed out in the claims.

30 In the accompanying drawings:

Fig. 1, is a longitudinal sectional elevation of a sewing machine with some of the parts in section and others in elevation,

Fig. 2, is a cross-section on the line 2—2,

35 Fig. 1,

Fig. 3, is a front elevation of the same parts of the machine as shown in Fig. 2,

Fig. 4, is a sectional elevation of the feed control mechanism showing the different adjustments, and

Fig. 5, is a detail view showing the gauge for the adjustments shown in Fig. 4.

The bed-plate 1, overhanging arm 2, needle-shaft 3, looper-shaft 4 and their adjuncts may be of any usual or approved construction and arrangement, and so also may be other parts shown in the drawing and not otherwise specifically described herein.

50 5 is a rock-shaft, made hollow and surrounding the looper-shaft 4, and having at its front end a crank arm 6 to engage the feed-dog. This shaft 5 herein referred to as the feed shaft, has at its rear end a crank arm 7 set quartering or otherwise thereon with relation to the crank arm 6. The looper-shaft 4 has a grooved crank arm 8 at its rear

end slidingly engaged by a roller 9 on the end of a connecting rod 10 which connects with a crank 11 on the needle shaft 3 and is operated by the latter to cause the revolution of the looper shaft. Between its ends the connecting rod 10 is formed with an elongated slot 12, and within this slot is a rocking member or fulcrum 13 loosely mounted upon a fixed pivot pin 14, the inner end of 60 said pin being screwed or otherwise fixed in a support 15 projecting within the hollow upright of the overhanging arm and preferably cast integral with one side of it. During the rotation of the needle shaft the crank 70 11 and fulcrum 13 impart an oscillating-reciprocating movement to the connecting rod 10, and cause the roller 9 to travel to and from the axis of the looper shaft in its sliding connection with the crank arm 8. 75 When the looper is picking up the loop the roller 9 is at or near the outer end of the crank arm 8, and is then revolving the looper shaft at a relatively slow speed. When the loop has been picked up the roller 80 9 moves inward along the crank arm 8 towards the axis of the looper shaft, and gradually increases the speed of revolution until the maximum speed of rotation is attained and then moves outwardly along the arm to 85 again decrease the speed of rotation to enable the looper to pick up the next loop. 16 is an arcuate lever or link pivoted centrally or thereabout on a screw or other pivot 17 fixed to the upright support 15. This lever or 90 link has an undercut or equivalent arcuate groove 18 in its face to receive a roller 19 on the upper end of a connecting rod 20 which is pivoted at 20^a to the crank arm 7, and this roller 19 enters and works in the 95 groove 18 of the lever or link 16. The arc of the groove 18 is concentric with the pivot 20^a for the free movement of the roller 19 when shifted therein, as hereinafter described.

100 The lever or link 16 has applied to one of its ends a pitman 21 which extends to and engages with an eccentric or crank 22 on the needle shaft which is set thereon at an appropriate angle to convert the rotary motion of the needle shaft into the proper rocking motion of the lever.

The connecting rod 20 has an elongated longitudinal slot 23 which receives a pin 24 on the end of one arm 25^a of a bell-crank 110 control lever 25, which is pivoted on a pin 26 supported at opposite ends in the upright

- part of the arm 2 and the support 15. The other arm 25^b of the bell-crank lever is extended through a vertically elongated slot 27 in the arm 2, and is provided with a 5 clamping nut 30 to hold it in its adjusted position. As the bell-crank lever is rocked it serves to selectively shift the roller end of the connecting rod 20 to one side or the other of the pivot or axis of the arcuate 10 lever or link 16, and thereby change the direction of movement of the feed dog and consequently that of the stitching, and it also serves to position the roller at points between the axis of the arcuate lever or link 15 and one or the other of its ends so as to vary the throw of the connecting rod 20, and consequently the length of the arc of movement of the crank arm 7 and the length of movement of the feed-dog and length of stitch. 20 The full and dotted lines Fig. 4, indicate possible variations of the sort referred to, and the curvature of the arcuate groove 18 being concentric with the pivot 20^a of the connecting rod 20 permits of the connecting 25 rod being shifted to reverse or change the length of stitch, while the machine is running.

To determine the limit of movement of the bell-crank lever 25, two adjustable stops 30 31 and 32 are arranged within the arm 2, one above and the other below the lever arm 25^b. These stops are arranged in alignment at one side of said lever arm, and each has a vertical screw threaded bore 33.

35 The arm 2, at the sides of the slot 27 is curved on a radius preferably from the center of the pin 26, as shown at 2^a, and above the curved part 2^a is a ledge 2^b, overhanging the stops. Formed through the 40 ledge 2^b is a bore 35 in line with the bores of the stops 31 and 32. Passing through the bore 35 and through the bores of the stops 31 and 32, is a screw 36, the lower part of which is left threaded, and the upper part 45 of which is right threaded, with a shoulder or unthreaded part 39 interjacent the threads to arrest the movement of the stops at what may be termed the zero position of the control lever 25.

50 On the outer end of the screw 36 is a knurled head 40, by which it is rotated to change the position of the stops 31 and 32. The arm 25^b oscillates between the stops 31 and 32 during the change of direction of 55 the feed and its degree of movement is limited in either direction by the adjustment of the stops.

On the outer end of the arm 25^b is the 60 clamping nut 30, which is adapted to bind against the curved part of the arm 2 and hold the control lever in its adjusted position, this nut being provided with a screw threaded bore to receive a bolt 30^a by which one end of a connecting rod 41 may be 65 coupled to the arm 25^b, the other end of the

connecting rod being coupled to a crank 43, projecting from the rock shaft 44. The rock shaft 44 is provided with a second crank 45, which constitutes the means by which the rock shaft is actuated to move the arm 25^b, 70 of the control lever, to the limit determined by the stops 31 and 32. The crank 45 is shown to be provided with a rod 46, having a knee band 46^a, by which it may be moved by the knee of the machine operator, when 75 the machine is driven by power to enable the machine operator to change the direction of the feed while the machine is running, without releasing the hands from the work. 80

The curved part of the arm 2 may have a graduated dial reading in both directions from a zero position as shown at 48 and the bell crank arm 25^b may be provided with a pointer 48^a, the pointer and the graduations 85 of the dial indicating the position of the control lever for the desired length of feed and consequently the length of the stitch to be made by the machine.

These graduations may be any sub-division of an inch, and when the stops are set the length of the stitch during the feed in one direction will be exactly the same as the length of feed in the opposite direction. By setting the stops for any desired length 90 of stitch, the machine will form a stitch of the desired length when feeding in one direction and when the direction is reversed the machine will form a stitch of the same length in the opposite direction, the change 95 of direction being possible when the machine is running.

The curvature of the arcuate lever or link 16 and its groove 18 being concentric with the pivot 20^a of the connecting rod permits 105 of the roller 19 being shifted from forward to reverse positions and vice versa to the limit of motion in either direction and any point intermediate the pivot 17 and these limits without disturbing the vertical reciprocation of the feed dog, and for this reason the curvature of the arcuate lever or link has been described from the pivot center 20^a and rocks on the pivot 17 during the shifting of the roller 19 to vary the length 110 of stitch and the direction of the feed. 115

Variations in details of construction and arrangement of parts are contemplated as being within the principle and scope of the invention as hereinafter claimed. 120

Having thus fully described my invention, what I claim as new and desire to secure by Letters Patent is:

1. In a sewing machine, a driving shaft, a 125 driven feed shaft, and a lever mechanism interposed between and connected with these shafts, comprising a connecting rod for the feed shaft and a rockable lever with which the connecting rod has adjustable connection, the combination of a control lever for 130

- the adjustment of the connecting rod, and adjustable means limiting the movement of the control lever and determining the length of stitch equally for the forward and reverse feeds. 5
2. In a sewing machine, a driving shaft, a driven feed shaft, and a lever mechanism interposed between and connected with these shafts, comprising a connecting rod for the feed shaft and a rockable arcuate lever with which the connecting rod has adjustable connection, the combination of a control lever for the adjustment of the connecting rod, and adjustable means limiting the movement of the control lever and determining the length of stitch equally for the forward and reverse feeds. 10
3. In a sewing machine, a driving shaft; a driven feed shaft, and a lever mechanism interposed between and connected with these shafts, comprising a connecting rod for the feed shaft, and a rockable lever with which the connecting rod has adjustable connection, the combination of a control lever for the adjustment of the connecting rod, and adjustable stops arranged on opposite sides of the control lever limiting its movement and determining the length of stitch equally for the forward and reverse feeds. 15
4. In a sewing machine, a driving shaft, a driven feed shaft, and a lever mechanism interposed between and connected with these shafts, comprising a connecting rod for the feed shaft and a rockable lever with which the connecting rod has adjustable connection, the combination of a control lever for the adjustment of the connecting rod, adjustable stops limiting the movement of the control lever and determining the length of stitch equally for the forward and reverse feeds, and a setting screw simultaneously positioning the stops. 20
5. In a sewing machine, a driving shaft, a driven feed shaft, and a lever mechanism interposed between and connected with these shafts, comprising a connecting rod for the feed shaft and a rockable lever with which the connecting rod has adjustable connection, the combination of a control lever for the adjustment of the connecting rod, and adjustable means limiting the movement of the control lever and determining the length of stitch equally for the forward and reverse feeds, a stationary dial, and a pointer 45 for the control lever, indicating the length of stitch. 50
6. In a sewing machine, a driving shaft, a driven feed shaft, and a lever mechanism interposed between and connected with these shafts, comprising a rockable lever, and a connecting rod for the feed shaft having an adjustable connection with the rockable lever, the combination of a bell crank control lever one arm of which has a moving connection with the connecting rod, a pair of 60
- adjustable stops arranged on opposite sides of the other arm limiting the movement of the control lever and determining the length of stitch equally for the forward and reverse feeds, and a setting screw simultaneously positioning the stops. 70
7. A sewing machine comprising adjustable means combined with the stitch control mechanism for determining the length of stitch simultaneously for the forward and reverse feeds, consisting of a lever for adjusting the stitch control mechanism, a pair of adjustable stops to limit the movement of said lever in opposite directions, and means for moving the lever between said stops to change the direction of the feed, consisting of a rock shaft having a pair of cranks, one of which actuates the rock shaft and the other of which is connected with the stitch control lever. 75
8. In a sewing machine the combination of a driving shaft and a driven feed shaft, with a compound lever mechanism interposed between and connected with these shafts, said lever mechanism comprising a connecting rod for the feed shaft, an arcuate lever concentric with the connection of said rod with the feed shaft, and a shiftable connection between the connecting rod and the arcuate lever. 80
9. In a sewing machine the combination of a driving shaft and a driven feed shaft, with a compound lever mechanism interposed between and connected with these shafts, said lever mechanism comprising a connecting rod for the feed shaft, an arcuate lever concentric with the connection of said rod with the feed shaft, a shiftable connection between the connecting rod and the arcuate lever, and a connection between the arcuate lever and the driving shaft. 85
10. In a sewing machine the combination of a driving shaft and a driven feed shaft, with a compound lever mechanism interposed between and connected with these shafts, said lever mechanism comprising a connecting rod pivotally connected with the feed shaft, an arcuate lever concentric with said pivotal connection, a fixed pivot on which the arcuate lever rocks and a shiftable connection between the connecting rod and the arcuate lever. 90
11. In a sewing machine the combination of a driving shaft and a driven feed shaft, with a compound lever mechanism interposed between and connected with these shafts, said lever mechanism comprising a connecting rod pivotally connected with the feed shaft, an arcuate lever concentric with said pivotal connection, a fixed pivot on which the arcuate lever rocks, a shiftable connection between the connecting rod and the arcuate lever, and a connection between the arcuate lever and the driving shaft. 100
12. In a sewing machine the combination of a driving shaft and a driven feed shaft, with a compound lever mechanism interposed between and connected with these shafts, said lever mechanism comprising a connecting rod pivotally connected with the feed shaft, an arcuate lever concentric with said pivotal connection, a fixed pivot on which the arcuate lever rocks, a shiftable connection between the connecting rod and the arcuate lever, and a connection between the arcuate lever and the driving shaft. 105

of a driving shaft and a driven feed shaft, with a compound lever mechanism interposed between and connected with these shafts, said lever mechanism comprising a 5 connecting rod having a pivotal connection with the feed shaft, an arcuate lever rockable on a fixed pivot and concentric with said pivotal connection, a shiftable connection between the connecting rod and the arcuate 10 lever, and a connection between the arcuate lever and the driving shaft.

13. In a sewing machine the combination of a driving shaft and a driven feed shaft with a compound lever mechanism interposed between and connected with these 15 shafts, said lever mechanism comprising a connecting rod having a pivotal connection with the feed shaft, an arcuate lever concentric with said pivotal connection, and a

roller for the connecting rod having a shift- 20 able connection with the arcuate lever.

14. In a sewing machine the combination of a driving shaft and a driven feed shaft with a compound lever mechanism interposed between and connected with these 25 shafts, said lever mechanism comprising a connecting rod having a pivotal connection with the feed shaft, an arcuate lever concentric with said pivotal connection, a roller for the connecting rod having a shift- 30 able connection with the arcuate lever, and a pitman connection between the arcuate lever and the driving shaft.

Toronto, Ontario, June 29th, 1920.
